UNITED STATES PATENT OFFICE.

EMIL COLLETT, OF CHRISTIANIA, NORWAY.

PROCESS OF OXIDIZING SULFITE BY MEANS OF AIR OR OTHER OXIDIZING-GAS.

1,076,747.

Specification of Letters Patent. Patented Oct. 28, 1913.

Application filed February 5, 1913. Serial No. 746,352.

To all whom it may concern:

Be it known that I, EMIL COLLETT, a subject of the King of Norway, residing at Christiania, Norway, have invented certain new and useful Improvements in Processes of Oxidizing Sulfite by Means of Air or other Oxidizing-Gas; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

This invention relates to the manufacture of sulfates such as sulfate of ammonia by treating sulfite in solution with oxygen or other oxidizing gases and has for its object a process by means of which the oxidation process is very considerably accelerated at the same time as it is made possible to employ apparatus of smaller dimensions than usually.

The invention is based upon the observation made by the applicant that the reaction velocity of the oxidation of sulfite by means of air or other gases containing oxygen is in a surprisingly high degree dependent upon the velocity of the gas current in the system, and according to the present invention this observation is utilized in the manner that by mechanical means a gas current of great velocity is maintained through the oxidation system. It has been found however that there are practical difficulties connected with passing great amounts of gas through the whole system and on the other hand it is not possible to obtain the desired velocity without passing a great volume of gas

through the oxidation system. Applicant therefore proceeds in such manner that the greater amount of the oxidizing gas is kept circulating in the oxidation system with the desired velocity while the amount of gas which in the unit of time is conducted to and from the whole system is much smaller.

An embodiment of the invention is diagrammatically illustrated in the accompanying drawing, in which A is the oxidation tower, through which the sulfite solution passes. B is the pipe, through which the principal amount of gas is maintained in circulation by means of the fan C, and D is a supply pipe for fresh amounts of oxidizing gas, which is supplied in limited quantities. E is the outlet pipe for the used gas.

I claim—

1. The process of oxidizing sulfite by means of an oxidizing gas, which consists in supplying the gas to an oxidation system and circulating the gas through the latter, at a greater speed than it is supplied to and withdrawn from the system.

2. The process of oxidizing ammonium sulfite by means of an oxidizing gas which consists in supplying and withdrawing the gas to an oxidation system, and circulating some of the supplied gas a plurality of times through the system at a greater velocity than that at which the gas is supplied and withdrawn.

In testimony that I claim the foregoing as my invention, I have signed my name in presence of two subscribing witnesses.

EMIL COLLETT.
